UNITED STATES PATENT OFFICE.

NILS O. STARKS, OF MADISON, WISCONSIN, ASSIGNOR TO THE FULLER & JOHNSON MANUFACTURING COMPANY, OF SAME PLACE.

CHECK-ROW CORN-PLANTER.

SPECIFICATION forming part of Letters Patent No. 390,529, dated October 2, 1888.

Application filed March 16, 1888. Serial No. 267,364. (No model.)

To all whom it may concern:

Be it known that I, NILS O. STARKS, a citizen of the United States, and a resident of Madison, in the county of Dane and State of Wisconsin, have invented certain new and useful Improvements in Check-Row Corn-Planters; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improvement. Fig. 2 is a side elevation of the same. Fig. 3 is a similar view at right angles to Fig. 2. Fig. 4 is a vertical sectional view on the line xx , Fig. 2. Fig. 5 is a similar view on the line yy , Fig. 4; and Fig. 6 is a view of the sector as it appears when viewed from the inner and under side.

Like letters of reference denote corresponding parts in the several figures.

My invention has relation to mechanism for operating the seed-slide in a check-row corn-planter of that class in which said slide is operated by mechanism actuated by means of a cord or chain provided with knots or buttons in the well-understood manner. My improvement, however, has no relation to that part of the mechanism which receives and again pays out the knotted cord or chain at the side of the machine, but has relation solely to the peculiar construction and combination of parts of the device, whereby a reciprocating motion is imparted to the seed-slide, as will be hereinafter more fully described, and particularly pointed out in the claims.

In the accompanying two sheets of drawings, the letters A A denote the usual mechanism which receives the knotted cord or chain at the front end and pays it out at the opposite end, the said cord or chain passing over the front pulley, B, then between the arms of the forked lever D, and then again out between the rear pulleys, C and E, where it leaves the machine. The bifurcated lever D has its fulcrum at F, and is provided with a bracket or projection, G, having a stud, H, upon which a rod, I, is pivoted. The rear end of this lever D is connected by a spring, d, to

the rearward end of the plate or bracket which supports the pulleys B and C.

Inasmuch as the several parts of this mechanism form no part of my improvement, a further description of the same is not deemed necessary in this connection, as its construction and operation will be fully understood by all persons conversant with the art to which it appertains.

Upon the middle of the machine, midway the parts A A, is a vertical sleeve, L, the lower part of which forms a cross-head, l, and trunnions m m, which are secured in suitable bearings or standards, J J.

Rocking sectors M M are journaled upon the trunnions, between their bearings and the cross-head of the sleeve, which cross-head forms abutments for the sleeves of the sectors, as seen more clearly in Fig. 4 of the drawings.

The said vertical sleeve is supported by brackets N N, bolted to any suitable part of the frame of the machine in such a manner that they will not be in the way of the rocking sectors during the operation of the machine.

Through this central vertical sleeve or collar L is inserted a shaft, O, the lower part of which is provided with a crank, P, having an adjustable wrist-pin, p, which is connected to the seed-slide (indicated in dotted lines) in the usual manner. The upper end of shaft O,

which projects above the sleeve, is provided with a pinion, o, engaging a cogged segment, Q, on the inner face of each of the rocking sectors M M. Each of these sectors above the aforesaid cogged segment is provided at each end with a beveled shoulder or offset, R, and also with a flange, S, which said flange is bent inwardly, so as to form a cam, T, the point of

which lies midway between the shoulders R R and is flush with the inner side of the sector. Each sector is provided with an arm, U, and a sleeve, U', whereby it is connected to its appropriate trunnion m. When the rocking sectors are placed in juxtaposition to each other, their inner flat faces will slide upon each

other, and their upper rounded bearing, which is provided with the shoulders or offsets R, will, by the cam-flanges S, form a groove or way adapted to receive the bent ends or shoes i i, whereby the rods I I are connected to the bifurcated levers at the sides of the machine.

These bent ends or shoes *i* of the connecting-
rods *I* are bent inwardly and pointed or
rounded, so as to engage recesses *r* in the off-
sets or shoulders *R*, and said rods *I*, where-
5 they engage with the sectors, are prevented
from becoming disengaged or slipping out of
the groove in which they play by means of the
bails or keepers *V* *V*, which are suitably fast-
ened to laterally-projecting ears of the central
10 sleeve, *L*, which said ears may also form
means of attachment for the supporting-
brackets *N* *N*.

At one end each of the rocking sectors is
preferably provided with a downwardly-pro-
15 jecting guide-piece, *W*, overlapping the under
side of the opposite sector and adapted to form
a stop when it comes in contact with the ends
of the cogged segment *Q* opposite.

The operation of my device is as follows:
20 When the machine is at rest, or in the position
shown in Fig. 1, the inner ends of the connect-
ing-rods *I* *I* will rest with their shoes *i* *i* in the
groove formed by the flanges *S* *S* between a
pair of shoulders on opposite sectors. When
25 the knot or button strikes the forked lever and
tilts it back, the connecting-rod on that side
of the machine will be pulled back against the
shoulder or offset with which it engages, thus
drawing the appropriate sector, of which this
30 offset forms a part, with it, and tilting the
sector to one side. This, of course, also tilts
the appropriate cogged segment *Q*, and as this
meshes with the pinion *o* a one-half revolution
is imparted to the vertical shaft *O* and the
35 crank at the lower end of the same, and where-
by, again, the seed-slide is operated by push-
ing it to one side. After the cord or button,
however, has become disengaged from its ap-
propriate lever, the tension of the spring *d*
40 will draw it back into its normal position,
whereby its connecting-rod *I* is pushed back,
so as to release the shoe *i*. On the backward
stroke of the rod on the way to assume its nor-
mal position the cam *T*, formed by the flanges
45 *S* *S*, will guide the free end of the rod over
upon the opposite sector, so as to bring it into
engagement with its appropriate shoe *i* of the
same, and thus at each reciprocation of the
forked or bifurcated lever its appropriate con-
50 necting-rod will alternately engage opposite
sectors, and thereby rock said sectors alter-
nately forward and back, thus rotating the
pinion with which these sectors engage alter-
nately in opposite directions. This movement
55 not only operates to reciprocate the seed-slide,
but as the pinion engages with both the sec-
tors the sector which has just been released
from the connecting-rod is brought back into
its normal position by the pinion, ready to re-
60 ceive the connecting-rod at the next stroke of
the machine. As both connecting-rods operate
precisely alike, it will be seen that the sec-
tors will be actuated in precisely the same man-
ner, whether one side of the machine is in use
65 or the other, one of the connecting-rods being
at rest while the other is in operation.

As the rocking sectors, with their several
parts, may all be cast in a single piece, it will
be seen that this device consists of but few
separate parts, which are inexpensive in their
70 construction, readily put together, and cer-
tain in operation, so that this improvement
may be manufactured at comparatively a small
cost, and will prove not only absolutely cer-
tain and effectual in use, but very strong and
75 durable, so that it is not apt to break or other-
wise get out of order, even if the machine is
subjected to exceptionally rough usage.

Having thus described my invention, I claim
and desire to secure by Letters Patent of the
80 United States—

1. In a check-row corn planter, the combi-
nation of rocking sectors with the connect-
ing-rods and bifurcated levers, whereby a re-
ciprocating motion is imparted to said rods,
85 substantially as and for the purpose shown and
set forth.

2. The combination of the rocking sectors
each provided with an arm and a sleeve, and
also with a cogged segment on its inner side,
90 the pinion engaging said segments, the pinion-
shaft, and the crank at the lower end of
the same for actuating the seed-slide, substan-
tially as and for the purpose shown and set
forth.

3. The combination of the rocking sectors,
the connecting-rods, a central sleeve having
ears upon its sides, and the bails or keepers
secured to said ears and straddling the sectors
and connecting-rods, substantially as and for
100 the purpose shown and set forth.

4. The combination, with the rocking sec-
tors having the studs or offsets at their ends,
and having the side flanges bent to form the
cam *T* midway between the shoulders, of the
105 rods *I* *I*, the ends of which are bent inwardly
and pointed, substantially as and for the pur-
pose shown and set forth.

5. The combination of the rocking sectors
having cogged segments *Q*, and each having
110 a downwardly-projecting guide-piece at one
end, with a pinion meshing with said segments,
substantially as and for the purpose shown and
set forth.

6. The combination of the central vertical
115 collar having a cross-head at its lower end,
the journals or pintles at opposite sides of said
cross-head, the rocking sectors provided with
trunnions working upon said journals and
having cogged segments on their inner sides,
120 the crank-shaft journaled in the central sleeve,
and the pinion at the upper end of said shaft,
adapted to mesh with the cogged segment,
substantially as and for the purpose shown
and set forth.

In testimony that I claim the foregoing as my
own I have hereunto affixed my signature in
presence of two witnesses.
